UNITED STATES PATENT OFFICE.

HENRY G. VOIGHT, OF NEW BRITAIN, CONNECTICUT, ASSIGNOR TO RUSSELL AND ERWIN MANUFACTURING COMPANY, OF NEW BRITAIN, CONNECTICUT.

KNOCKDOWN BRACKET.

SPECIFICATION forming part of Letters Patent No. 728,339, dated May 19, 1903.

Application filed August 14, 1902. Serial No. 119,650. (No model.)

To all whom it may concern:

Be it known that I, HENRY G. VOIGHT, a citizen of the United States, residing at New Britain, in the county of Hartford and State of Connecticut, have invented certain new and useful Improvements in Knockdown Brackets, of which the following is a specification.

My invention relates to improvements in knockdown brackets; and the objects of my improvement are simplicity and economy in construction and efficiency and convenience in use.

In the accompanying drawings, Figure 1 is a central vertical section of the wall and shelf plates of my bracket with a side elevation of the brace. Fig. 2 is a detached plan view showing the upper end of the wall-plate. Fig. 3 is a front elevation of the wall-plate on a reduced scale. Fig. 4 is a reverse plan view of the shelf-plate. Fig. 5 is a rear end view of the shelf-plate on the same scale as Fig. 1. Fig. 6 is a rear elevation of the complete bracket in a slightly-modified form on a reduced scale. Fig. 7 is a vertical section of the corner portion of the said bracket on the line $x-x$, Fig. 6, the scale being the same as in Fig. 1. Fig. 8 is a plan view of the said corner portion.

30 A designates the wall-plate, B the shelf-plate, and C the brace. The body portion of these parts may be of any ordinary form. They are intended to be formed of sheet metal and may be provided with any ordinary or desired form of strengthening-beads. In the preferred form the upper end of the wall-plate A is provided with front straps 9 35 10, swaged or pressed forwardly from the plate, and with a rear strap 11 in the plane 40 of the plate proper, so as to form a vertical socket to receive the tongue 12 on the rear end of the shelf-plate B. I prefer to make the upper edge of the front strap 9 a little below the extreme upper end of the 45 wall-plate A, whereby the corners 13 of the said upper end may project upwardly as far as the upper face of the shelf-plate B, as shown in Fig. 1.

The wall and shelf plates may be provided

with any desired number of screw-holes 15, 50 which may be countersunk in any proper manner. The tongue 12, that extends at right angles to the shelf-plate B, is provided with a screw-hole 14, which when the said tongue is in place registers with the upper one 55 of the screw-holes 15 of the shelf-plate, so that when a screw is passed therethrough the said screw will positively lock the wall and shelf plates together. The wall and shelf plates in the particular form shown are each provided 60 with two brace mortises or slots 16 and 17, and the brace C is provided at each end with a tenon 18 and hooked lug 19. The ends of the brace stand at a right angle to each other, and the hooked lug 19 at the lower end of the 65 brace projects downwardly, while that at the upper end of the brace projects outwardly, or, in other words, both of the hooked lugs project outwardly from the corner formed by the junction of the wall and shelf plates. The 70 tenons 18 substantially fill the mortises or slots 16 in the wall and shelf plates, while the hooked lugs at their longest part are of a length that will pass through the mortises or slots 17, so that they may be hooked to the 75 wall and shelf plates by engaging the metal at the outer ends of the mortises or slots 17, the projecting portion of the said hooked lugs being on the inner side of the said plates, as shown in Fig. 1.

80 The bracket shown in Figs. 6, 7, and 8 is the same as in Figs. 1 to 5, excepting that there is no rear strap or wall for the socket of the tongue 12, that the screw-holes 15^a are countersunk by swaging, so that a bur 20 is 85 formed at the rear on the metal around the said screw-holes, and that the screw-hole 14^a in the said tongue is countersunk on its front face, so as to receive the bur 20 of the upper one of the screw-holes of the wall-plate, with 90 which upper hole the screw-hole 14^a registers. The upper corners 13 of the wall-plate extend back of the shoulders 21 at the rear ends of the shelf-plate, and thus prevent the tongue from working backwardly toward the rear of 95 the wall-plate before the bracket is screwed to the wall.

In order to assemble either form of the

bracket herein shown, the lower end of the brace is locked to the wall-plate by passing the hooked lug 19 through the mortise or slot 17, then forcing it down to engage the metal 5 at the lower end of the said slot, and then pushing the tenon 18 into the mortise or slot 16 to lock the hooked lug. The tongue 12 of the shelf-plate is then inserted in its socket; but the inner end of the shelf-plate 10 is left a little higher than its locked position until after the shelf-plate has been crowded rearwardly far enough to enter the hooked lug 19 through the mortise or slot 17 of the shelf-plate. After the said lug passes through 15 the said slot the shelf-plate is moved forwardly to engage the hooked lug with the metal at the outer end of the said slot and to bring the tenon 18 under the mortise 16. The rear end of the shelf-plate is then lowered 20 into its final position to positively lock the parts in place, as shown in Fig. 1. The parts are thus firmly held together, and the bracket is ready for being screwed to the wall in the ordinary manner, in doing which one of the 25 screws passes through the registering holes of the wall-plate and tongue 12 of the shelf-plate, so that the two plates are firmly locked together. The bracket may be knocked down again after removing it from the wall by 30 first raising up the inner or rear end of the shelf-plate to disengage the tenon 18 from its mortise 16, then springing the parts to force the upper end of the brace rearwardly to disengage the hooked lug from the upper end 35 of the brace, then lowering the upper end of the brace to withdraw the tenon 18 at its lower end, then lifting the brace upwardly to withdraw the hooked lug, and finally pulling the tongue of the shelf-plate wholly out of its 40 socket in the wall-plate.

By my improvement the parts are cheaply constructed by cutting and shaping from sheet metal. They may be shipped in their knockdown form, so as to occupy but little 45 space in transportation. They are readily put together for use and are very strong and substantial when in use.

It is apparent that some changes from the

specific construction herein disclosed may be made, and therefore I do not wish to be understood as limiting myself to the precise form of construction shown and described, but desire the liberty to make such changes in working my invention as may fairly come within the spirit and scope of the same. 55

I claim as my invention—

1. A knockdown bracket consisting of wall-plate, shelf-plate and brace, formed of separate pieces for locking together, the said shelf-plate having the vertical tongue at its inner 60 end and the said wall-plate having the vertical socket with walls for engaging both sides and both edges of the said tongue, substantially as described.

2. A knockdown bracket consisting of wall-plate, shelf-plate and brace, formed of separate pieces for locking together, the said wall and shelf plates having at their meeting ends a tongue on one of the said parts and a tongue-receiving socket on the other of the said parts 65 with registering screw-holes in the said tongue and wall of the said socket, substantially as described.

3. A knockdown bracket consisting of wall-plate, shelf-plate and brace, formed of separate pieces for locking together, the said brace having at each end the tenon 18 at one part and an outwardly-extended hooked lug at another part distinct from the said tenon, the said wall and shelf plates having connecting 75 devices at their meeting ends arranged for permitting the inner end of the shelf-plate to be lifted within its connections with the wall-plate, the said wall and shelf plate each having a mortise 16 for the said tenons within 80 which the said tenons fit closely, and slots 17 other than the said mortises, for receiving the hooked lugs of the brace, whereby the hooked lugs of the brace may be positively locked to the wall and shelf plates by lowering the inner 85 end of the shelf-plate into its final position on the wall-plate, substantially as described.
